SLIP COVER FOR FURNITURE

Arthur Oppenheimer, Jr., New York, N. Y.

Application September 4, 1935, Serial No. 39,092

6 Claims. (Cl. 155—182)

This invention relates to slip covers for upholstered furniture and more particularly to slip covers which are provided with surplus material for securing them to the articles of furniture.

5 An object of the invention is to provide an improved slip cover of the indicated type which can be manufactured in a few stock sizes and which is so constructed that it will fit satisfactorily on upholstered pieces of furniture having 10 widely varying dimensions.

Another object of the invention is to provide a unitary slip cover of the indicated type in which the elements thereof are so constructed and arranged that the slip cover can be placed on and 15 removed from an article of furniture with facility and which when positioned on the article of furniture, will not become disarranged or untidy during usage.

Other objects and advantages of the invention 20 will appear from the following description taken in connection with the accompanying drawings in which Fig. 1 is a front perspective view of an over-stuffed chair having a slip cover thereon embodying the present invention; Fig. 2 is a rear view 25 of the covered chair shown in Fig. 1 with a portion of the rear panel of the slip cover folded over to illustrate one means for securing the slip cover on the chair; Fig. 3 is a top plan view of Fig. 1, partially in section, one side of the seat 30 and inner back panels being shown in untrucked position; Fig. 4 is a bottom view of the chair, illustrating how the slip cover is secured on the underside of the chair; Fig. 5 is a perspective view 35 of the covering for the seat cushion; Fig. 6 is a vertical section taken through the arms and seat panels of the slip cover showing the arrangement of such panels on the chair, and Fig. 7 is a vertical section taken at right angles to that of Fig. 6, illustrating the arrangement of the seat and 40 back panels on the chair.

The invention is herein illustrated as embodied in a slip cover for an over-stuffed wing chair of conventional construction having a separable or removable seat cushion. Preferably the seat 45 cushion is enclosed in a separate casing, as illustrated in Fig. 5, but it may be covered by the seat panel of the slip cover in the same manner that the seat portion of the chair is covered by such panel as will be hereinafter explained.

50 In accordance with the invention, the slip cover is constructed from several fashioned pieces of cloth assembled and stitched together to provide a unitary structure comprising generally a front panel 10, front arm panels 11 and 12, outer side panels 13 and 14, inner side panels 15 and 16,

outer and inner back panels 17 and 18, respectively, outer wing panels 19 and 20, inner wing panels 21 and 22, seat panel 23, a skirt 24 to surround and cover the lower portion of the chair and attachments or flaps 25 which are secured 5 under the seat portion of the chair by the ribbons or tapes 26.

The covering section for each arm of the chair includes a front arm panel, which covers the front face of the arm, an outer side panel, which 10 covers the outer side of the arm, and an inner side panel, which covers the inner surface of the arm. As shown in the drawings, the inner side panels 15 and 16 are formed so that they extend over the tops of the chair arms, the seams 27 15 between such panels and the outer side panels 13 and 14, respectively, extending lengthwise of the arms along the outer upper portions thereof. The lower edge portions of the inner side panels 15 and 16 are designed to be tucked into the 20 spaces between the chair arms 28 and the seat portion 29, as is clearly shown in Fig. 6. The front edges of the inner side panels 15 and 16 are sewed to the front arm panels 11 and 12, respectively, the seams 30 between such panels 25 extending from the upper edge of the front panel 10, along the inner edges of the front faces of the arms of the chair and over the front upper edges of the arms to the seams 27. The upper rear edge of the panels 15 and 16 are preferably 30 sewed to the lower edges of the inner wing panels 21 and 22, respectively, the seams 31 between such panels being preferably formed on the inside of the slip cover so that there is no projecting material at these junctures. The inner side edges 35 of the panels 15 and 16 are tucked into the spaces between the chair arms 28 and the back cushion 32.

The front edges of the outer side panels 13 and 14, which cover the outer sides of the chair arms, 40 are sewed to the front arm panels 11 and 12, respectively, the seams 33 between such panels, together with the seams 30, conforming with the general configuration of the front faces of the arms of the chair. As is shown more clearly in 45 Fig. 2, the rear portions of the outer side panels 13 and 14, extend around to the rear of the chair, the upper edges of such rear portions being sewed to the lower edges of the outer wing panels 19 and 20, respectively, so as to form the seams 34. 50 The rear edge portion of the outer side panel 13 is sewed to a fastening strip 35 provided preferably with snap sockets 36 and is secured in position on the rear of the chair when the button snaps 37 mounted on the fastening strip 38 of the 55

outer back panel 17 are snapped into place in the snap sockets 36. The rear edge of the outer side panel 14 is sewed to the opposite edge of the outer back panel 17, forming the seam 39.

- 5 The inner edge of the outer wing panel 20 is likewise sewn to the outer back panel 17 immediately above the rear portion of the outer side panel 14, so that the seam section 40 between such panels forms a continuation of the seam 39.
- 10 The outer and top edges of the outer wing panel 20 are sewn to the outer and top edges, respectively, of the inner wing panel 22, forming a seam 41 having the configuration of the outer edge of the wing of the chair. The inner edge of 15 the wing panel 22 is sewn to the inner back panel 18 downwardly a short distance only from the top of the chair, forming the seam 42 which is turned inwardly so that there is no projecting material along this juncture. The remainder of 20 the inner edge portion of the wing panel 22 is unattached and is tucked in between the wing cushion 43 of the chair and the back cushion 32.

The inner edge of the wing panel 21 is attached to the inner back panel 18 in the same manner as the wing panel 22, to form the short seam 44, the remainder of the inner edge portion of such panel being tucked in between the wing cushion 45 of the chair and the back cushion 32. The outer and top edges of the wing panel 21 are 30 secured by a seam 46 to the outer and top edges respectively of the outer wing panel 19 in the same manner that the outer and top edges of the wing panels 20 and 22 are secured together. The inner edge of the outer wing panel 19 is sewn 35 to the outer back panel 17 downwardly to a point approximately midway between the upper and lower edges of such panel, the seam 47 between the outer wing and back panels 19 and 17 respectively, forming a continuation of the seam 48 between the side panel 13 and the fastening strip 35 so that the appearance of the back of the slip cover will be uniform when it is fastened in position on the chair.

The outer back panel 17 is secured at its upper 45 edge to the upper edge of the inner back panel 18 by a line of stitching which forms a seam 49 extending along the upper rear edge of the chair, such seam being continuous with the seams 41 and 46 of the wing panels, as shown in Figs. 1 50 and 2.

The inner back panel 18 and the seat panel 23 are formed from an integral piece of material of sufficient width so that the sides of the panel portion 18 may be tucked in between the wing and 55 back cushions of the chair (see Fig. 3) from the lower ends of the seams 42 and 44 down to the tops of the chair arms and also in between the arm cushions and the back cushion and so that the sides of the panel portion 23 may be tucked 60 in between the arm cushions and the seat portion 29, as shown in Fig. 6. The length of the piece of material forming the panel portions 18 and 23 is preferably such that a tuck of sufficient size may be formed between the seat portion 29 65 and the back cushion 32 (see Fig. 7) to enable such tuck to obtain a firm anchorage between such cushions, whereby the panel cushions 18 and 23 are maintained securely in place on the chair. The front edge of the panel portion 23 is sewn 70 to the upper edge of the front panel 10 to form the seam 50, which extends across the upper front edge of the seat portion 29. The sides of the front portion of the seat panel 23 are secured to the inner side panels 14 and 15 to form the seams 75 51, as shown more clearly in Fig. 3, and to pre-

vent any likelihood of separation of the parts at these points during usage.

The front panel 10 is secured at its side edges to the inner sides of the front arm panels 11 and 12 by lines of stitches which form the seams 52, as 5 shown in Fig. 1.

The skirt 24 is secured to the bottom edges of the front panel 10, front arm panels 11 and 12, outer side panels 13 and 14, and the outer back panel 17, the ends of the skirt terminating at 10 the meeting edges of the panels 13 and 17, to which the fastening strips 35 and 38 are secured.

The skirt may be plain or of such length as to 15 enable it to be pleated, as shown in the drawings, and should be of such width that it extends downwardly to within a short distance of the floor level. It is of course within the contemplation of the invention to omit the skirt entirely. Secured to the slip cover by the same seams which secure the skirt to the lower ends of the slip cover, are 20 the four fastening members or flaps 25 which are adapted to be anchored on the underside of the chair in any suitable manner as by the tapes 26 shown in Fig. 4 to remove the bogginess from the cover, thus providing a form fitting cover. 25 While I have shown the flaps as being triangular in shape, it will be understood that they may be formed in any suitable fashion, so long as they are capable of exerting a uniform pull along the bottom edges of the slip cover.

30 From the above, it will be seen that the arrangement of the several panel sections of the slip cover is such that the operation of applying the cover to an article of furniture, can be effected expeditiously and quickly, it being only 35 necessary to place the cover over the chair or the like, so that the several parts thereof are covered by their proper panels, then secure the fastening strips 35 and 38 together, after which the flaps 25 are secured in position on the underside of the chair so that the outer panels of the cover are tightly drawn into their approximate proper positions and lastly tucking the unattached portions of the panels 15, 16, 18, 21, 22 and 23 and the surplus material contained in the integrally formed panels 18 and 23 down into the crevices between the cushions of the chair, so that such panels are stretched tightly against the surfaces of their respective cushions and are in proper position. The tucking in of the panels 45 50 may, of course, be done before anchoring the cover on the underside of the chair, if the user so chooses.

The slip cover of the present invention is preferably made of a stretchable material, such as 55 jersey cloth, stockinet, elasticized fabric, etc., which when in position on the fabric covering of the chair cushions clings closely to the outer surfaces of the cushion covering fabric. Thus, when a slip cover of the present invention is placed on 60 an article of furniture and properly secured in position, the material of which the panels are constituted is tightly stretched over the chair surfaces in close contact therewith and due to the clinging quality of such material will be securely 65 held in proper position and cannot be wrinkled or displaced while the chair is in use. Also, by reason of this construction, I am enabled to accomplish the desirable object of supplying a slip cover which will fit articles of furniture of widely 70 different sizes snugly and neatly. It is, therefore, not necessary to measure a piece of furniture carefully as is generally done when a cover is to be made, but, on the contrary, my covers can be made up in a single size for each type of furni- 75

ture. The several panel sections are preferably so arranged that the direction of greatest stretch of the material used is in the direction of the tucked-in portions of the panels and the line of pull of the flaps at the bottom edges of the cover. The flaps, of course, may also be made of a resilient or stretchable fabric.

While I have shown in the drawings one form of the invention for the purposes of illustration, it is obvious that the various parts may be arranged and organized differently from the precise arrangement of the elements herein shown and described, without departing from the spirit and scope of my invention. Furthermore, I do not wish to restrict myself to a slip cover made wholly of resilient fabric as those portions which are to be subjected to the greatest wear, such as the inner panels or the top portions of the arms may be made of a tougher fabric, such as chintz, cretonne, or linen. Other combinations of resilient or knitted and woven fabrics may be also produced for the purpose of obtaining different and pleasing effects in the design of the slip cover. I therefore, desire that the present embodiment of the invention be considered in all respects as illustrative and not restrictive, reference being had to the appended claims whose purpose it is to include and embrace any such modifications.

I claim:

- 30 1. A slip cover for an upholstered article of furniture provided with arms, including an outer back portion for the rear of the article, a cover compartment for each arm, the outer portion of each of said arm compartments being secured at its rear edge to a side edge of said back portion and the inner portion of each of said compartments having a free rear edge adapted to be tucked into the space between an arm and the back of the article and having a free bottom edge adapted to be tucked into the space between such arm and the seat of the article, said cover including a front portion adapted to cover the front face of the seat of the article and being secured to said arm compartments, a seat and inner back portion secured at one end to said front portion and at its other end to said outer back portion and being free along its side edges, approximately from the front end thereof to the upper ends of the free rear edges of the inner portions of the compartments, said seat and inner back portion having a length greater than the combined depth of the seat and height of the back to provide surplus material to be tucked into the space between the back and the seat and being provided with sufficient surplus material along the free portions of its edges to enable it to be tucked into the spaces between the arms and the back and seat of the article, and means associated with the lower edges of the outer back portion, the outer portions of the arm compartments and the front portion and cooperating with the tucked in parts of the inner covering portions to maintain the several portions snugly in position on the article.
- 45 2. A slip cover as claimed in claim 1, in which said seat and inner back portion is free along its edges to a point above the upper ends of the free rear edges of the inner portions of the compartments and adjacent the top of the back.
- 50 3. A slip cover for an upholstered article of furniture provided with arms and having a fixed upholstered seat portion, said cover comprising an outer back portion for the rear of the article, a cover compartment for each arm, the outer portion of each of said arm compartments being

secured at its rear edge to a side edge of said back portion and the inner portion of each of said compartments having a depth greater than the depth of the arm to provide surplus material to be tucked into the space between the arm and back and having a height greater than the arm to provide surplus material to be tucked into the space between the arm and the fixed upholstered seat portion of the article, said cover including a front portion adapted to cover the front face of the seat of the article and being secured to said arm compartments, a seat and inner back portion secured at one end to said front portion and at its other end to said outer back portion and having a length greater than the combined depth of the seat and height of the back to provide surplus material to be tucked into the space between the back and the fixed seat portion of the article, said seat and inner back portion being provided with sufficient surplus material along its side edges to enable it to be tucked into the spaces between the arms and the back and fixed seat portion of the article, the said portions of the cover being made of a fabric material capable of substantial expansion from its normal condition and capable of clinging closely to the covering fabric of the article, whereby the tucked-in parts of such portions are effectively secured in the spaces between the arms, back and the fixed seat portion of the article and creeping or slipping of such portions on the covering fabric of the article is prevented, and means associated with the lower edges of the outer back portion, the outer portions of the arm compartments and the front portion and cooperating with the tucked-in parts of the inner covering portions and the adhering action of the stretchable fabric material to maintain the several portions of the cover snugly in position on the article.

4. A slip cover as claimed in claim 3, in which the said portions thereof are made of knitted fabric material inherently stretchable in both directions so as to snugly conform to the contour of the back, arms and fixed seat portion of the article.

5. A slip cover as claimed in claim 3, in which the means associated with the lower edges of the outer back portion, the outer portions of the arm compartments and the front portion comprise a plurality of inelastic fastening members adapted to hold the stretchable material under tension during the use of the article.

6. An upholstered chair comprising a seat portion, a back portion and arms, a covering for said chair comprising a cover portion for the inner and outer surfaces of the back portion of the chair, compartment portions for both the inner and outer surfaces of said arm portions of the chair, and a covering portion for the top surface of the seat portion of the chair, said covering portions being connected, said covering comprising material inherently stretchable in both directions whereby the covering may be drawn over the chair under tension both in the direction of the width and the length of the chair, the portion of said cover overlying the top edge of the back portion being under tension and in close surface engagement with said top edge of the back portion, said cover including surplus material tucked between the lower front surface of the back portion and the rear surface of the seat portion and on both sides of the chair between the side surfaces of the seat portion and the lower portions of the chair arms, said tucked-in portions being retained in such tucked-in position

by frictional engagement of said cover material and the juxtaposed upholstered chair material, and means associated with the lower portions of the cover for securing the same relative to the bottom of the chair, the respective portions of said covering overlying the back, arm and seat portions of the chair being in frictional surface engagement with the said corresponding portions of said chair and tightly stretched over the said chair portions, the portions of the covering during the use of the said chair stretching to conform to the contour of such portions of the chair

which are depressed from their normal configuration and resuming their normal condition when the depressed portions of the chair return to their normal contour, the frictional and tensional surface contact between the upholstering material and the stretchable material of said covering retaining said materials in substantially smooth, wrinkleless relation when said chair-back and seat are released from the depressive action resulting from the use of the chair. 10

ARTHUR OPPENHEIMER, JR.
